UNITED STATES PATENT OFFICE.

LESLIE W. BLOCK, OF WEBSTER GROVES, MISSOURI.

SHINGLE.

Application filed July 14, 1927. Serial No. 205,632.

My invention relates to shingles and, while a shingle embodying the improvements which I have invented may be made of any material my invention is more particularly directed to improvements in composition shingles.

Heretofore numerous attempts have been made to provide a shingle and more particularly a composition shingle which can be quickly and easily laid and yet which will when laid form a substantial and weather-proof roof. In composition roofs it is especially desirable that the shingles be laid symmetrically because they are sometimes made in different colors and in order to get a desired combination of colors or a design in different colors it is necessary that the shingles be laid in perfect symmetry according to a predetermined pattern.

Such shingles as have been made in attempts to overcome these difficulties and to achieve the required purposes have been failures in that if the shingle was made so that it could be quickly and easily laid the shingles when laid would not be symmetrical and if the shingles were made so as to be laid symmetrically the proper laying thereof would be hard, and consequently, would take a great deal of time and labor and, therefore, would be excessive in cost.

The objects of my invention are to provide a shingle which is so constructed and arranged that it may be quickly and easily laid in any desired form.

Several forms of shingles embodying my invention are shown in the accompanying drawings wherein similar letters are used to designate similar parts: Figs. 1 and 2 show one form of shingle; Figs. 3 and 4 show another form of shingle; and Figs. 5 and 6 show the method of laying the form of shingle shown in Figs. 1 and 2.

Referring to the figures each form of shingle embodying my invention consists of a substantially flat section A of weatherproof material, which section is preferably of substantially rectangular shape and, preferably, is of substantially uniform thickness throughout its area. Each shingle also has a raised portion B, preferably, positioned near the upper end of the shingle and centrally transversely of the weather face thereof and arranged to extend upwardly from the weather face of the shingle a distance substantially equal to the thickness of the shingle. Preferably at the lower end of the raised portion B are formed lugs C which, as shown, project transversely outwardly from the sides of the raised portion B. Each side edge of the shingle has an inwardly extending notch D of a shape and size to conform to the shape and size of the lugs C, all for the purposes more fully hereinafter set forth.

The raised portion B may be formed on the weather face of the shingle in any one of several different ways but I have found that the cheapest and best way of forming it is by stamping out a part of the upper marginal surface of the shingle to conform to the desired contour of the raised portion and bending this stamped out portion back against the weather face of the shingle and then fixing it in bent back position by cement or any other suitable means. In the form of shingle shown in Figs. 1 and 2 of the drawing, the raised portion has been formed in this way. The only objection to forming the raised portion as described above is that when the shingles are used to form a roof, as shown in Figs. 5 and 6 and as will be more fully hereinafter described, a portion of the roof will be formed of only one thickness of weatherproof material. If it is desired that there be two thicknesses of weatherproof material at all points of the roof the raised portion may be formed as in the form of shingle shown in Figs. 3 and 4 of the drawings. In this form the shingle has an extension piece E protruding outwardly from the upper end thereof. A separate piece of weatherproof material of a size and shape to conform to the size and shape of the desired raised portion and to extend along the extension E is cut separately and then fixed to the weather face of the shingle by cement or any other suitable means. In either form of shingle the operation of forming a roof therewith is the same. This operation is as follows:—The laying of the shingles is started at the eaves and the first and second courses are, preferably, laid at the same time, as shown in Fig. 6. Adjacent shingles in the first course are spaced transversely from one another when the raised portions B of the shingles in the first course are placed against the sides of the shingles in the second course, as shown. The shingles comprising the second course are spaced longitudinally with relation to the shingles comprising the first course by placing the lugs C of the shingles in the first course in the notches D in adjacent shingles in the second course, all as shown. I prefer that the notches D in the shingles be arranged

so that the shingles comprising the second course will extend downwardly and cover the notches D in the shingles comprising the first course. After the first and second courses are laid as described and nailed the other courses are laid until the top of the roof is reached, and the laying of these courses is effected in the same way as the laying of the first two courses with the raised portions B on the shingles spacing the adjacent shingles in a course transversely from one another and with the lugs C and notches D in register spacing the adjacent courses longitudinally in relation to one another.

15 It may be readily seen that with the use of my shingles a roof may be quickly and easily formed and the shingles which form the roof will be laid in perfect symmetry. Since the raised portion B is on the weather 20 face of the shingle it is not necessary to feel by moving the shingle around when the parts are in register but, to the contrary, the person laying the shingles may readily see when the sides of adjacent shingles in one course 25 are against the sides of the raised portion B of the shingles in the adjacent lower course and, likewise, the person can see when the lugs C are in the notches D.

Also, when a roof is laid the engagement 30 between the lugs C and notches D will, as clearly shown in Fig. 5, prevent rain or wind from passing upwardly between adjacent shingles in a course and the roof will be much more weatherproof than a roof formed 35 in the old way.

As stated above, only two forms of shingles embodying my invention are shown in the drawing but it may be readily understood that I do not purpose to limit myself to any 40 particular forms of shingles since shingles may be made in various shapes and sizes within the limits of the claims included below and yet not deviate from the spirit of my invention.

45 What I claim as new and desire to secure by Letters Patent, is:—

1. A shingle consisting of a section of

weatherproof material of substantially uniform thickness throughout its area, said shingle having attached to its weather face and substantially centrally transversely thereof a flat portion extending upwardly a distance substantially equal to the thickness of said shingle, said portion being of a uniform width equal to the distance it is desired to position the shingles of the next upper course, and said portion having a lug extending transversely outwardly from each side thereof and said shingle having a notch in each of its side edges of a size and shape to conform to the size and shape of said lugs, whereby the said notches may receive the lugs on the attached portions of the next lower course.

2. A roof formed of a plurality of shingles laid in courses, each of said shingles consisting of a section of weatherproof material of substantially uniform thickness throughout its area and each of the shingles in a course having on its weather face and substantially centrally transversely thereof a raised portion extending upwardly a distance substantially equal to the thickness of said shingle, and said raised portion being otherwise adapted and arranged to engage the 75 sides of adjacent shingles in an upper adjacent course and thereby space said adjacent shingles transversely in relation to one another, and each of said shingles having lugs extending outwardly transversely from each side of said raised portion and also having a notch formed on the side edges of said shingle and said lugs and said notches being so adapted and arranged that the lugs on a shingle in one course may be engaged in the 80 notches in adjacent shingles in a lower adjacent course whereby the shingles comprising said one course will be spaced longitudinally from the shingles comprising said adjacent course.

In witness whereof I have signed my name to the foregoing specification.

LESLIE W. BLOCK.
